Patented Jan. 28, 1919.

FIG. B

FIG. 1

INVENTOR:
Horace G. Lazelle

BY
Pierre Gaines
ATTORNEY

UNITED STATES PATENT OFFICE.

HORACE G. LAZELLE, OF SEATTLE, WASHINGTON.

SUBMERSIBLE TOY.

1,292,618.

Specification of Letters Patent. Patented Jan. 28, 1919.

Application filed October 18, 1917. Serial No. 196,854.

To all whom it may concern:

Be it known that I, HORACE G. LAZELLE, a citizen of the United States, residing at Seattle, in the county of King and State of Washington have invented certain new and useful Improvements in Submersible Toys, of which the following is a specification.

The object of this invention is to provide an amusement device made to resemble an object such as a torpedo boat or whale, and to provide means whereby it may be caused to simulate the movements and actions of the same in water.

The construction of my invention is simple and inexpensive and entirely under the control of the operator.

The invention consists in the novel construction and arrangement of parts herein-after described and claimed.

20 In the drawings, Figure 1 is a view shown partly in side elevation and partly in longitudinal section of a preferred form of my invention. Fig. 2 is a side elevational view of the vessel as represented in Fig. 1, shown floating in water and indicating in dotted lines positions the vessel will assume in diving and ascending toward the surface.

25 In the drawings, 5 represents a vessel of tin or an equivalent made to represent a whale which is chosen as a good type of object with which to describe the invention, but the invention is applicable to other types.

30 The interior of said vessel is divided by a partition 6 disposed somewhat nearer to the rear end of the vessel to afford compartments 7 and 8, the former being of considerably larger capacity and communicating with the exterior through an opening such as 9, the peripheral wall of the smaller compartment 8 being imperforate.

35 Within the vessel is provided an inflatable rubber sack 10, the larger portion of said sack being disposed in the forward compartment 7 and having a relatively smaller portion 10¹ extending through an opening 11 of said partition into the rear compartment 8, as shown.

40 12 represents a tube extending through the vessel wall at 13 and making communicative connection between the sack 10 and the resilient hollow rubber ball 14, said ball being provided with an aperture 15 which serves,

upon occasion, for the inlet and discharge of air. 55

16 represents a tube extending from near the bottom of compartment 8 through partition 6 to a nozzle attachment 17 connected in the vessel shell, as shown.

16 In operation, the vessel is placed in a body 60 of water represented by W in Fig. 2, whereupon the water will enter through opening 9 into compartment 7 and thence through partition opening 11 into compartment 8, a small amount of air remaining in compartment 8 above said opening.

By being thus flooded with water, the vessel will descend in a position such as represented by dotted lines A in Fig. 2, and cause the vessel to descend. The operator 70 squeezes the ball 14 to effect the inflation of the sack 10, during which action the aperture 15 is closed by the operator's finger.

In being inflated, the sack is expanded uniformly and primarily closes the partition opening 11 to prevent any outflow of water therethrough from the compartment 8. In the continued inflation of the sack, that portion within the compartment 7 will be distended to occupy more space, as indicated by dotted line 10², than is accomplished by the sack portion 10¹ with respect to the other compartment 8, resulting in the displacement of almost all the water from compartment 7, consequently providing a relatively large amount of buoyancy to the head end of the vessel so that it will ascend to the surface in about the position in which it is indicated by dotted lines B in Fig. 2. 85

By forcing more air into the sack, the portion 10¹ thereof is distended to occupy a space such as indicated by dotted lines 10³ in Fig. 1, causing the surrounding water to be expelled through tube 16 and nozzle 17 resembling the spouting of a whale at the surface. It is apparent that the vessel may be brought to the surface by suitably regulating the pressure on ball 14 and the spouting may be caused to occur from the time its nose appears above the surface until it is submerged 100 in the following diving action.

To cause the vessel to dive, the operator still holding his finger over ball aperture 15, allows the ball 14 to reassume its normal expanded position, withdrawing the air from the sack 10, water thereupon entering the 105

compartment 7, while no water can enter the compartment 8 until the sack has contracted sufficiently to provide a passage about the sack in the partition opening 11, the tube 16 5 meanwhile being water sealed.

From the foregoing it is evident that the regulation of the ball 14 dictates both the trim and the vertical movements of the vessel, beside serving to spout the water through 10 the nozzle 17.

What I claim is—

1. In a submersible toy, the combination with a hollow vessel, and a compressed air supply means, of devices provided interiorly 15 of the vessel and rendered operable by said means to regulate the buoyancy of the vessel in a body of water and also serving to control the longitudinal trim of the vessel to selectively have either end of the same up- 20 permost.

2. In a toy, the combination with a vessel divided into two compartments, of pneumatic devices including an inflatable sack extending into both of said compartments 25 whereby water may be displaced from the interior of the vessel to regulate the longitudinal trim of the latter when in water.

3. In a toy, the combination with a vessel divided into two compartments, of pneumatic means including an inflatable sack whereby water may be successively displaced 30 from both of said compartments when the vessel is submerged in water.

4. In a submersible toy, the combination with a hollow vessel, having an opening for 35 the admission and discharge of water, of

pneumatic means for expelling the water from said vessel to render it buoyant and serving subsequently to regulate the inclination of the vessel. 40

5. In a submersible toy, the combination with a vessel, an inflatable sack therein, and means to supply air under pressure into said sack, of means provided in the vessel and influencing the functions of the sack whereby by the inflation and deflation of the same is controlled to vary the longitudinal inclination of the vessel in its descending and ascending movements. 45

6. In a submersible toy, the combination with a vessel divided by an apertured partition into two compartments of unequal size arranged one in front of the other, the forward of said compartments having an opening communicating with the space surrounding the vessel, of an inflatable sack provided in the forward compartment and extending through the aperture of said partition into the rear compartment, said rear compartment communicating with an outlet in the forward compartment, and means to introduce air into the sack to inflate the same whereby water is displaced from the forward compartment and ejected through said outlet from the rear compartment. 50 55 60 65

Signed at Seattle, Washington, this 8th day of Oct., 1917.

HORACE G. LAZELLE.
